ATTORNEY.

UNITED STATES PATENT OFFICE.

HARRY A. ARTHUR, OF PHILADELPHIA, PENNSYLVANIA.

OPERATION-CONTROL RECORD.

1,336,120.

Specification of Letters Patent.

Patented Apr. 6, 1920.

Application filed April 21, 1919. Serial No. 291,701.

To all whom it may concern:

Be it known that I, HARRY A. ARTHUR, a citizen of the United States, and a resident of Philadelphia, in the county of Philadelphia and State of Pennsylvania, have invented an Improvement in Operation-Control Records, of which the following is a specification.

My invention relates to improvements in means designed to enable persons engaged in manufacturing or other analogous business to ascertain readily and quickly the condition of work or other forms of transactions which are being put through or effected in the plant or establishment.

For instance, assuming that a manufacturing concern receives orders for certain goods to be manufactured which require first a foundry operation and second a machinery operation, it may become necessary from time to time for the central office to answer queries as to the condition of the orders that are in the factory or other point in the establishment. In such cases, obviously, it would be very desirable if means were at hand which would enable someone in the central office to ascertain readily and at a glance the condition of the work—whether it still is in the foundry or whether the work in the foundry has been completed and forwarded to the machine shop department and if it has been forwarded to the latter department, whether it is still there or whether it has been completed and shipped.

Broadly speaking, it is the object of my invention to provide means whereby this information may, at all times, be present at some designated place, such as the central office, and in such shape as to be readily available.

A further object of my invention is to provide means whereby the different departments of an establishment, in which work of one kind or another is to be performed, may readily report to the central office completion of work which shall have been performed and completed in such departments.

A further object of my invention is to provide means including certain external, visible characteristics, the presence or absence of which, ascertainable by a mere glance, indicates to the person making the examination the condition of the particular piece of work in which such person may be interested.

Other objects and advantages of my invention will be pointed out in the detailed description thereof which follows or will be apparent from such description.

In order that my invention may be readily understood and its practical and commercial advantages may be fully appreciated, reference should be had to the accompanying drawings in which I have illustrated different forms of embodiment thereof; that is, different means by the employment of which the system involved in my invention may be practised. It will be understood that the means for visually indicating the condition of any particular piece or item of work which may be on hand in a plant may be varied and changed within the scope of the claims without departing from my invention. It is to be understood therefore that my invention is not limited to the exact arrangement of cards or the particular characteristics thereof as shown in the drawings and as described in the specification.

In the drawings:

Fig. 1 is a perspective view of a series of cards constituting the master file of the system;

Fig. 2 is a similar view of a series of cards constituting a dummy file and relating to the machine shop of a manufacturing plant;

Fig. 3 is a corresponding view of a series of cards relating to the foundry department;

Fig. 4 is a face view of a foundry record card;

Fig. 5 is a face view of a machine shop record card;

Fig. 6 is a face view of a card withdrawn from the foundry dummy file;

Fig. 7 is a corresponding view of a card withdrawn from the machine shop dummy file;

Fig. 8 is a perspective view of a series of cards showing a modified construction and arrangement thereof for visually or graphically indicating the condition of work in a manufacturing or other business establishment;

Fig. 9 is a face view of a machine shop record card;

Fig. 10 is a like view of a foundry record card; and Figs. 11 and 12 are face views of cards withdrawn from the file shown in Fig. 8.

Referring to Figs. 1 to 7 inclusive of the

drawings, 1 designates the master file cards each of which is numbered, the numbers beginning with the numeral 1 and running as high as may be desired. The cards are arranged in numerical sequence as indicated. In Fig. 1 it will be noted that the first card shown is numbered 875 and as indicated, the remaining cards therein are numbered in sequential order. Upon the master cards is placed the data relating to an order upon the receipt of the same. These master cards may contain such information as desired. In the system as illustrated they contain certain permanent data as follows:—

15   "Master record card."
               "Customer's name."
               "Customer's order No."
               "Description (brief)."
               "Delivery promised."

20   This data may be changed, if desired or if required by the nature of the transactions of which record is being kept. In the spaces following each of these permanent headings 25 the appropriate information should be inserted. The orders are entered upon the consecutive cards and at the end of the day after the last order the date card for the following day should be inserted in the file. 30 For instance, assuming that the last order for December 31st shall have been received and entered, the clerk in charge of the file or file room should insert immediately after the card containing the data respecting the 35 order a card bearing a projection having thereon the date "Jan. 1" as shown at 2 in Fig. 1 of the drawings.

In order to facilitate the location of a card or cards bearing any particular number the files are provided at intervals with 40 cards having projections thereon upon which numbers are shown. For instance, in Fig. 1 one of the cards is provided with a projection having thereon the number 900 as 45 shown at 5 and at a succeeding or following place in the file another card is provided with a projection bearing thereon the number 950, as shown at 6. It is obvious that any number intermediate these two numbers 50 or between any other two numbers which may be displayed as these are displayed may be readily located by any person in charge of the file or any other person who may have occasion to examine the same. Upon 55 receipt of an order the data concerning the same is entered upon a master card and thereafter orders are sent to the foundry and machine shop departments, such orders bearing the same number as the master 60 card, together with other information such as the customer's name and the work to be done. The order having been received in the foundry department the work is proceeded with and when completed, report 65 thereon is forwarded to the main office where

the master and dummy card files are kept. The foundry department is provided with cards numbered consecutively, the numbers corresponding with those upon the cards of the master file and of the dummy files in the 70 main or central office of the plant or establishment. These cards should be of some color fixed upon, such as green as shown in Fig. 4 of the drawings, different from the cards in the foundry dummy file in the central office. These cards have certain data or headings printed thereon as for example the following:—

    "Foundry record card."
              "Completed."
              "Reasons for delay."
              "Signed by."

80

Upon completion of the work in the foundry, a report is made to the central 85 office by placing appropriate information upon the foundry record card such as is shown at 10 and forwarding the same to the central office. For instance, in the space following "Completed" on said card the 90 date Jan. 20, 1919 may be inserted and if there has been delay as to which it is desirable that an explanation shall be given, such explanation may be given after the words "Reasons for delay" (if any) and the name 95 of the person making the report may be placed in the space following the words "Signed by" on the card. Upon receipt of this green card at the central office it will be inserted in lieu of a card number 900 in 100 the foundry dummy file 11, the cards of which are of pink or red color. The withdrawn card 12 is shown in Fig. 6. Assuming that the work which has thus been completed in the foundry department is to be 105 machined, it is then forwarded to the machine shop where such machining operations as may be necessary are performed. After the machining operations shall have 110 been performed the machine shop superintendent or some other person fills in a card 13 such as is shown in Fig. 5 which is purple in color and forwards the same to the central office indicating thereon the date of completion of the work and inserting thereon information as to the reasons for any delay which may have occurred. Upon receipt of this card at the central office it is substituted for a card of the same number 115 in the machine shop dummy file 14 the cards 120 of which are of a contrasting blue color. The card withdrawn from the machine shop dummy file is shown at 15 in Fig. 7.

These withdrawn dummy cards 12 and 15 may be destroyed or they may be placed 125 in the master card file in association with the master card of corresponding number, as may be preferred.

It will be noted that the two dummy files 11 and 14 are each provided with extra or 130

divisional cards having thereon projections at their upper edges upon which are printed respectively the dates Jan. 1, Jan. 2 and the numbers 900 and 950 as in the master file 5 series of cards 1.

It may be that certain orders have been made special and that it is desirable to keep special track of the same. This may be done by placing upon the cards pertaining 10 to these orders in the master and dummy files detachable tabs as indicated at 20 and 21. The presence of these tabs would indicate that the orders to which the cards upon 15 which they are placed relate are special and shall be rushed through as quickly as possible or that they are entitled to some other special consideration.

It will be noted that the series of master 20 cards 1 are white and that the cards of the foundry and machine shop dummy files are pink or red and blue respectively and that the cards upon which reports are made from the foundry department and from the machine shop to the central office are respectively 25 green and purple. It will be understood however, that cards of any other color or colors may be employed. The idea is that there shall be contrasting colors so that any person in the central office by a mere 30 glance at the dummy files may know the condition of the work in the particular departments to which those files relate. For instance, if he examines the foundry dummy file shown in Fig. 3 and finds that all of the 35 cards therein are pink he knows at once that no reports of work completed have been received from the foundry department, because he does not find therein any green cards which have been substituted for the 40 pink or red cards of that file. On the other hand, if he finds this file made up of green cards he knows that all of the work comprised within the dates in which he may be interested has been completed in the foundry. 45 The machine shop dummy file is capable of telling the same story in identically the same way and by reason of the employment of cards of contrasting colors the information required may be obtained without 50 the necessity of a laborious examination and reading of various orders, files, etc. It is apparent that the dummy files display graphically or visually the condition of the work in the particular department of the 55 establishment to which they relate.

Instead of the separate dummy files as shown in Figs. 2 and 3 these files may be combined in a single file with the master card file shown in Fig. 1. In the latter suggested arrangement dummy cards for the foundry and for the machine shop departments would be placed in the same file as the master cards and all the cards of the same number would be associated or placed in 60 approximate relation with respect to each

other. The principle of operation would not be changed but would remain just as previously described.

In Figs. 8 to 12 inclusive of the drawings I have illustrated a different means by 70 which a series of cards may be made to indicate graphically the condition of work upon the various orders which may have been received by a concern and which may be in process of being filled. In the scheme 75 or system as described in connection with Figs. 1 to 7 inclusive contrasting colors of the cards are depended upon for indicating graphically or visually the condition or status of the work wherever it may be in the 80 establishment whereas in the system as illustrated in Figs. 8 to 12 inclusive, all of the cards may be of the same color. In the latter case the cards are provided with certain characteristic features of construction 85 by means of which they indicate graphically the condition or status of the work. In the file of cards illustrated in Fig. 8 it will be observed that they are numbered in sequential order and that there are three 90 cards of each number. One of these is the master record card, one the machine shop record and the other the foundry record card. The two last mentioned cards; namely, the machine shop record and the 95 foundry record card correspond to the cards found in the dummy files shown in Figs. 2 and 3 respectively. Each of these cards as well as the master record card is provided with a projection as indicated at 30. These 100 cards are separated at intervals into groups by cards having projections 31 upon which appear the dates just as in the arrangement shown and described in connection with Figs. 1 to 7 inclusive. These date-bearing 105 cards are inserted following the last order of each day and each card thus inserted bears the date of the succeeding day upon which it is expected that orders will be received. Upon the receipt of an order at the central 110 or other office where orders are received and handled, if it is found to bear the customer's order number, this number together with the customer's name and such other information as may be thought desirable is placed 115 upon the master record card, which as has already been pointed out bears a number. Thereafter, assuming that the first work in filling the order is to be done in the foundry, instructions are sent to the foundry de- 120 partment in the usual form giving the number corresponding to the number of the master card on which the data concerning the said order previously shall have been placed, also the customer's order number 125 and any other information which it is desirable should be transmitted to the foundry. There is kept in the foundry department a series of cards having printed thereon the words "Foundry record card," also head- 130

ings calling for further information as described in connection with Figs. 1 to 7. One of these cards is indicated at 35 in Fig. 10. These cards are sequentially numbered to correspond with the numbers upon the cards in the central or other office in which the orders from customers are received and handled. They are not provided with projections as are the cards in the central office, shown in Fig. 8. Upon the completion of the work in the foundry, one of these cards is filled out by placing in the spaces following the headings referred to the appropriate information. The card indicated in Fig. 10 is the number 2 foundry record card.

Assuming that after the work shall have been finished in the foundry department it is to pass through a machining operation, it would then be forwarded to the machine shop. This department also is provided with a series of machine shop record cards, one of which is shown at 36 in Fig. 9. These cards are similar to the foundry record cards 35 and they each bear a heading "Machine shop record card" together with certain headings as indicated. In the spaces following these headings certain appropriate information may be placed. After the work is finished in the machine shop a card such as is shown in Fig. 9 is properly filled out and forwarded to the central or other office where the complete record is kept just as in the case of the foundry card. These cards as they are received in the main or other office are substituted for the dummy machine shop cards bearing like numbers in the file shown in Fig. 8. As has been described and as is apparent from an inspection of Fig. 8 of the drawings the cards originally in the central office file are each provided with projections having thereon numbers corresponding to the number of the master card. Upon receipt of the correspondingly numbered cards from the foundry and machine shop they are substituted for the foundry and machine shop dummy cards having the projections so that upon an inspection of a file such as shown in Fig. 8 it is apparent at a glance whether or not all of the work in the two departments in question has been completed and reports to that effect forwarded to the main or other office and filed. The cards such as the cards 37 and 38 in Figs. 11 and 12 after having been removed from the file may be destroyed or not as desired.

Upon inspection of Fig. 8 it will be observed that the cards pertaining to the foundry and machine shop which bear the numbers upon the tabs in Figs. 11 and 12 have been withdrawn and the cards without tabs or projections received from the foundry and machine shop substituted therefor. It is likewise apparent that the foundry and

machine shop cards have been received in 65 the central office in the cases of the orders 7 and 8 and substituted for the cards originally in the file and which bore projections having thereon the numbers 7 and 8.

As in the system or scheme illustrated in 70 Figs. 1 to 7 inclusive, if it is desired to make certain orders special and to indicate this fact in the file, this may be done by placing special tabs 40 upon the master cards pertaining to these orders.

In both systems or schemes it is apparent 75 that means is provided whereby at a glance a person may ascertain the condition of the work for which the same may be designed.

I have described my invention in connection with a scheme for keeping track of or for supplying knowledge with respect to the foundry and machine shop departments. However, it will be understood that the system or scheme is applicable to other departments and to other kinds of work. The scheme may be extended to include not only the foundry and machine shop departments 85 but the shipping department and other 90 departments as well. As already indicated the scheme is not confined to a manufacturing establishment but is applicable in any case where it is desirable that a main or central office shall at all times be able to 95 ascertain the condition of transactions of any nature which may be in hand provided the transactions are such as are susceptible of being designated by numbers or numerical reference.

100 While the means employed in the scheme illustrated in Figs. 8 to 12 inclusive for indicating visually and at a glance the condition of work of whatever character in an establishment is different from what is 105 shown in Figs. 1 to 7 it is apparent that the principle of operation of the two schemes or systems is identical and that either may be employed as may be desired, the two schemes functioning in identically the same manner.

110 The dummy foundry and machine shop cards in the file shown in Fig. 8 which are associated with the respective master record cards and which are provided with the projections at their upper edges, having numbers thereon corresponding to the numbers upon the master record cards with which they are associated, correspond to the cards of the dummy files shown in Figs. 2 and 3 of the drawings and whenever in the claims 115 the words "dummy file" or "dummy card" are employed they will be understood to include not only the cards in the files shown in Figs. 2 and 3 but also the similarly functioning cards comprised in the file shown 120 in Fig. 8.

I claim:

1. An operation-control card record file

comprising a master card file in which the cards are sequentially numbered, dummy cards associated with said master cards and being correspondingly numbered and cards 5 adapted to be substituted for the said dummy cards for indicating when work to which the said third mentioned cards relate has been completed.

2. An operation-control card record file 10 system comprising master record cards sequentially numbered, one or more groups of dummy cards having colors contrasting with the color of the master record cards and with each other and other cards adapted to 15 be substituted for the said dummy cards said other cards having colors contrasting with the said dummy cards for which they are substituted.

3. An operation-control card record file 20 system comprising master record cards sequentially numbered, dummy cards having means whereby they form a contrast with the master record cards and other cards adapted to be substituted for the said 25 dummy cards which other cards contrast with the said dummy and master record cards.

4. An operation-control card record system 30 comprising master record cards sequentially numbered, one or more series of cards having numbers corresponding to the numbers upon the master record cards and one or more series of cards having characteristics whereby they form a contrast with the

cards of the second named series and being 35 adapted to be substituted therefor.

5. An operation-control card file system comprising a master record card file, the cards therein being sequentially numbered, a plurality of dummy files the color of the 40 cards in any file differing from the color of the cards in each of the other files and each dummy file pertaining to a particular department of the business to which the system relates and cards of contrasting colors 45 containing information thereon as to the status of the work in the department from which the said cards emanate which are adapted to be substituted for cards in the proper dummy file. 50

6. An operation-control card file system, comprising a master card file, the cards therein being sequentially numbered, a plurality of dummy files, the characteristics of the cards in any file differing from the characteristics 55 of the cards in each of the other files, and each dummy file pertaining to a particular department of the business to which the system relates, and cards of contrasting characteristics containing information 60 thereon as to the status of the work in the department from which the said cards emanate, which are adapted to be substituted for cards of the proper dummy file.

In testimony that I claim the foregoing 65 as my invention I have hereunto set my name this 17 day of April, 1919.

HARRY A. ARTHUR.
